PUTTING TARGET DEVICE

Arthur E. Stokes, Red Bank, N. J.

Application December 3, 1952, Serial No. 323,839

5 Claims. (Cl. 273—177)

This invention relates to a target device and, more particularly, to a putting target to provide golfers with a device for putting practice which is usable indoors and which indicates whether or not the ball is traveling with a speed and accuracy suitable to drop into a cup on a golf green.

In simulating putting green conditions indoors, one difficulty has been that it is not practical to countersink the cup target in the floor surface. Therefore, the rim of the cup target has necessarily been raised above the floor surface. To provide means for the ball to approach the rim of the cup, some prior putting target devices have included ramps which led to the cup. In such devices, the ramp created the artificial condition, which would not normally exist on a golf green, of an abrupt rise near the cup. This artificial condition required an additional force when putting, a force greater than would normally be required on an actual putting green; resulting in the mistraining of the golfer. Furthermore, with the use of a cup target, it is generally necessary to empty the cup after each successful put or, in the case of an unsuccessful put, the ball will return down the ramp and will interfere with successive puts so that, in effect, it is necessary to clear either the approach or the cup after each put and the person practicing, therefore, cannot retain a set stance and have the opportunity to put several balls from that stance so that he may fully analyze the control factors of aim and speed.

Other devices in which actual cups were not used, although providing means for indicating when the ball was correctly aimed, did not provide suitable means for gauging whether or not the ball was moving at the proper speed to drop into the cup, and, therefore, did not completely simulate actual conditions.

An important object of this invention is to provide a target for convenient training away from the golf course, which simulates conditions found on a putting green.

Another object is to provide a device which will determine when a ball is correctly aimed and is moving at a proper speed to drop into a cup, such device being simple and inexpensive to make and adapted for placement on a flat surface such as a floor.

A more general object is to provide a target device in which the accuracy of direction and speed control of missiles such as balls directed at the target may be gauged and indicated.

The target device of this invention in its broader aspects includes a target area with a displaceable sensory signal disposed in the target area and operable by a predetermined displacement by missiles, such as balls, entering the target area. The sensory signal may be a bell which is suspended so that it is displaceable with respect to its clapper. The invention also contemplates the deflection of balls from the target area after their entry has been signalled so that additional balls may be directed at the target area without stopping to clear the target area or the approach thereto. The means for ball deflection include the bell itself, which after displacement will swing back like a pendulum and deflect the ball away from the

2

target area in a direction away from the approach because of the circular shape of the bell. In addition, stationary deflectors may be positioned in the target area to direct balls toward the sides and the rear of the device.

5 The invention also contemplates the inclusion of an additional or auxiliary signal which may be of the visual type, such as a flag, which is operable by excessive displacement of the bell, selected amounts in selected directions, the auxiliary signal indicating when the ball putted 10 to the target is moving too rapidly to enter the cup. The operative engagement means between the bell and the auxiliary signal provide for different amounts of speed depending upon the direction in which the putted ball is moving. For a more complete description of the invention, reference is made to the drawings wherein:

Fig. 1 is a plan view of a device embodying the invention;

Fig. 2 is a sectional view of the device taken along the line 2—2 in Fig. 1;

20 Fig. 3 is another sectional view taken along the line 3—3 in Fig. 1;

Fig. 4 is a perspective view of the operative connection means between the bell and the auxiliary signal;

Fig. 5 is a diagrammatic plan view of the device.

25 The device shown in the figures includes a base portion 10 to which is connected a bracket 11 extending upward from the rear of the base, at the left in Figs. 1, 2 and 5, and extending forward over the base 10. A target area 12 is defined on the base portion 10. When the device is 30 used for a putting target, the target area defined may be suitably marked on the base 10 as a circle of the same diameter as a standard golf cup, i. e. 4 1/4 in. in diameter. A sensory signal device in the form of a bell 13 having a clapper 15 may be suspended from the bracket overhanging the base portion 10 by means of a member 16 which includes a hook 17 and a threaded shaft portion 18, the threaded shaft 18 being secured to the bracket by nuts 19 threaded thereon, one nut being disposed on each side of the bracket 11 through which the threaded member 18 extends. The axes of the bell and the clapper are coaxially disposed with respect to the center of the target area 12 so that the bell is suspended above the target area and inside its perimeter.

35 Mounted on the base 10 is a raised portion 21, which extends from the rear of the base 10 forward into the target area as best indicated in Figs. 1, 2 and 5. The raised portion defines ball deflecting surfaces 22 and 23 which converge at an apex 25 forming a wedge extending into the target area 12.

40 The clapper 15 and the bell 13 are mounted for pivotal displacement on the hook 17, as indicated in Figs. 2 and 3; and, the clapper 15 is mounted for pivotal displacement on the hook 26 of the shank 27 which extends through the center of the bell. Clapper 15 includes an enlarged disc bell-striking member 28 so that 45 only slight displacement of the bell is necessary for contact of the clapper element 28 with the bell.

The target device is adapted for approach from front side 43, at the right side as viewed in Figs. 1, 2 and 5.

45 A cam plate 30 mounted on the shank 27, as best shown in Figs. 2, 3, and 4, has a rearwardly extending cam surface 31 and two upwardly turned cam surfaces 32. The cam plate may be fixed to the shank 27 of the bell and moves when the bell is displaced for a purpose to be described hereinafter.

50 An auxiliary signal device 33 which may be of a visual type is mounted in the bracket 11 upon a pivot shaft 35. The auxiliary signal 33 includes an upwardly disposed signal area 36 which may be distinctively marked as a visual signal. Said signal is adapted to move upward 55 through an opening 37 which is provided in the bracket 11 when the auxiliary signal 33 is actuated. A shoulder

portion 38 may be provided for retaining the member 36 in the slot in its lowered position, as shown in Figs. 1 and 2 in full line. The auxiliary signal 33 has a rearwardly extending counter-balancing portion 40 upon which may be mounted counter-balancing elements such as the nuts and screws 41 attached to the arm 40, as shown in Figs. 1 and 2. A slot 42 is provided in the forward arm 39 of the signal 33 to permit the member 16 to extend loosely therethrough. The forward portion 39 of the signal member 33 is provided with a generally flat undersurface as best shown in Figs. 2 and 3 which is adapted to be engaged by the cam surfaces 31 and 32 of the cam plate 30 when the latter is tilted by excessive displacement of the bell.

When the bell is displaced excessively, as indicated by the dotted line in Fig. 2, so that the cam plate 30 engages the undersurface of the forward element 39, the auxiliary signal member 33 is caused to pivot so that the forward arm 39 rises and the upright signal area 36 moves upwardly through the slot 37 so that the signal area 36 is visible above the bracket 11.

In operation, the device is placed on the floor with the base portion in contact with the floor or upon a rug, or if outdoors, upon the ground. The person using the device takes up a stance a suitable distance from the target in line with the approach or front side 43 of the device and puts a ball in the direction of the target. If the ball is properly aimed it will move into the target area 12 and contact the bell. If it has been struck with sufficient force to enter a golf cup, the bell will be displaced sufficiently for the clapper 15 to contact the bell 13 and give the proper auditory signal. After the ball strikes the bell, the displaced bell returns to its original position and will tend to swing a corresponding distance in the opposite direction from the direction in which it was displaced. This reaction of the bell acts to push the ball out of the target area and thereby clear the target area for successive puts. The fact that the bell 13 is circular will cause the ball to be deflected out of the general approach area 43 for the ball tends to glance off to one side or the other. If the ball proceeds past the bell without being pushed aside by the return of the bell, one of the deflector faces 22 or 23 will act to deflect it to the side and the rear of the target area. Either or both the bell and the deflector member 21, therefore, act to clear the target area and particularly the approach side 43 of such area.

As best shown in Fig. 5, the bell may be of a diameter such that the center of gravity of the ball 50 must be moved within the target area in order to properly displace the bell for signalling a satisfactory put, thereby indicating that the ball would normally fall into the cup.

It will be understood, therefore, from the foregoing that the bell will indicate when a correctly aimed ball has entered the target area with sufficient speed to enter a golf cup.

The auxiliary signal 33 is provided to indicate when the ball entering the target area exceeds the speed which is suitable for dropping into the cup and therefore when the auxiliary signal is actuated and the signal area 36 becomes visible, the person putting will know that although the ball was correctly aimed, its speed was excessive and the ball would have traveled across the cup or would have rimmed it without dropping in.

It will be appreciated that a ball which approaches a cup on a direct line with the center of the cup may travel at a considerably greater speed and drop in, than a ball which is slightly out of line with the center of the cup, for the ball out of line with the center of the cup will frequently "rim" the cup and fail to drop in. To accurately reproduce this condition, the cam plate 30 which engages the underside of the forward portion 39 of the member 33 has raised side cam surfaces 32. The effect of the arrangement of the cam plate is such

that when the bell is struck from the side, the displacement of the bell and the cam plate need be very slight before the cam surface 32 engages the forward portion 39 and causes the signal 36 to rise, whereas the bell may be struck with considerably greater force when the ball is traveling in a direction substantially on line with the center of the target area.

It will be appreciated from the foregoing that by use of the device described, a person may gauge his aim and speed of ball and thereby improve his putting ability. When only the bell sounds, the person "putting" knows that the ball was properly aimed and was moving at the proper speed to enter a golf cup. However, if the bell sounds and the signal 36 rises into view, the person is thereby informed that although the ball was correctly aimed, it was moving too fast to be retained in the cup. If the bell does not sound, the person knows that the ball was not correctly aimed or had insufficient force to enter the cup.

In order to permit the fine adjustment of the cam plate 30, the nuts 19 may be adjusted so that the shank 16 may be raised or lowered to reduce or increase the space between the cam surfaces 31 and 32 of the cam plate and the cam-engaging surface of the member 33.

It has been found practical to produce the base and bracket portions of the described device from a single sheet of metal. The deflector member 21 may be of metal, wood, plastic, or other suitable material.

The invention described may be carried out by means other than the described apparatus and the various elements may be changed and arranged in a different manner from each other without departing from the spirit or scope of the invention.

It will be noted that the invention and the described apparatus embodying the invention fulfills the objects of providing a target device for convenient putting practice, and that the invention provides a means of determining when the ball has been correctly aimed and is moving at a proper speed to drop into a cup on a golf green. It will also be appreciated that the invention can be embodied in a relatively simple and inexpensive device which in addition to having particular utility as a golf practice putting device also may be adapted generally as a target device to test the skill in direction and speed control of missiles directed at the target.

In accordance with the provisions of the patent statutes, I have herein described the principle of operation of the invention, together with the elements which I now consider the best embodiments thereof, but I desire to have it understood that the structure disclosed is only illustrative and the invention can be carried out by other means. Also, while it is designed to use the various features and elements in the combinations and relations described, some of these may be altered and modified without interfering with the more general results outlined.

Having thus described my invention, I claim:

1. A putting target device, comprising a flat base, a target area defined thereon, a bell and clapper, a bracket extending above the target area displaceably supporting the bell and clapper above and within the target area defined on the base, the bell being operable by a predetermined amount of displacement of the bell with respect to the clapper when the bell is engaged by balls entering the target area, an auxiliary signal operable by another predetermined amount of displacement, a cam plate mounted on the bell and engageable with the auxiliary signal for effecting the displacement of said signal, said other predetermined amount when the bell is displaced selected amounts in selected directions.

2. A putting target device for indicating accuracy and speed of the ball, comprising a target area for receiving balls from a selected direction on one side of the target area, means for deflecting balls from the target area after they have entered said area, a first signal means for indicating when a ball has entered the

target area, and a second signal means operable by the first signal for indicating when the ball exceeds a selected speed from said selected direction and when it exceeds other selected speeds from other selected directions.

3. A putting target device for indicating accuracy and speed of the ball comprising a target area for receiving balls from a selected direction on one side of the target area, a first signal means for indicating when a ball has entered the target area, and a second signal means operable by the first signal for indicating when the ball exceeds a selected speed from said selected direction and when it exceeds other selected speeds from other selected directions.

4. A putting target device for indicating accuracy and speed of the ball comprising a flat target area for receiving balls from a selected direction on one side of the target area, means for deflecting balls from the target area after they have entered said area, a first signal means including a bell and clapper for indicating when a ball has entered the target area, and a second signal means operable by the first signal for indicating when the ball exceeds a selected speed from said selected direction and when it exceeds other selected speeds from other selected directions.

15

25

5. A putting target device for indicating accuracy and speed of the ball comprising a flat target area for receiving balls from a selected direction on one side of the target area, means for deflecting balls from the target area after they have entered said area, a bracket extending above the target area, a bell and clapper suspended from said bracket above and within the target area for indicating when a ball has entered the target area, and a trippable signal operated by movements of said bell greater than predetermined amounts in predetermined directions as caused by balls striking the bell and clapper at various angles and various speeds for indicating that such balls have exceeded predetermined speeds from predetermined angles.
